FISH LURE

Paul Bennett, Wilmette, Ill.

Application April 12, 1952, Serial No. 19,305

Term of patent 14 years

(Cl. D31—4)

To all whom it may concern:

Be it known that I, Paul Bennett, a citizen of the United States, residing at Wilmette, county of Cook, State of Illinois, have invented a new, original, and ornamental Design for Fish Lure, of which the following is a specification, reference being had to the accompanying drawing, forming a part hereof.

The dominant features of my design reside in those portions shown in full lines.

I claim:

The ornamental design for a fish lure, as shown and described.

PAUL BENNETT.
